Primary Examiner — Karen S Acker*Assistant Examiner* — Clare Ann Gannon(74) *Attorney, Agent, or Firm* — Law Office of Ilya Libenzon(57) **CLAIM**

The ornamental design for a blanket with fingers, as shown and described.

DESCRIPTION

FIG. 1 is a front perspective view of the blanket with fingers of the present invention.

FIG. 2 is a front plan view thereof.

FIG. 3 is a rear plan view thereof.

FIG. 4 is a top elevation view thereof.

FIG. 5 is a bottom elevation view thereof.

FIG. 6 is a right-side elevation view thereof; and,

FIG. 7 is a left-side elevation view thereof.

The broken lines depict portions of the blanket with fingers that form no part of the claimed design.
